UNITED STATES PATENT OFFICE.

ALBRECHT VOGT, OF ROCHESTER, NEW YORK.

DESIGN FOR DRESS-EDGING.

SPECIFICATION forming part of Design No. 30,165, dated February 7, 1899.

Application filed September 30, 1898. Serial No. 692,342. Term of patent 7 years.

To all whom it may concern:

Be it known that I, ALBRECHT VOGT, a citizen of the United States, and a resident of Rochester, in the county of Monroe and State 5 of New York, have invented a certain new and original Design for Dress-Edging, of which the following is a specification.

The drawing, to which reference is hereby made, represents a face view, on an enlarged 10 scale, of a piece of dress-edging embodying my design.

The leading features of my design consist in a dress-edging having the shape shown in the drawing and the ornamentation, also 15 shown in the drawing, of a series of X-shaped figures upon the body of the web of said dress-edging.

In the drawing, A is the web portion, and B is the fringe or brush portion thereof, ex-

tending from one edge of said web portion. 20 Upon the surface of the web portion A appears the design of a series of X-shaped figures visible upon the surface of the web and formed by a series of threads c^2 c^3 . The threads a of the web A and the threads producing the series of X-shaped figures are of 25 such appearances or colors or characters of material as to create a visible contrast between the threads a and the threads c^2 c^3 , so that each X-shaped figure is visible upon the 30 background of the web A.

What I claim is—

The design for dress-edging, substantially as herein shown and described.

ALBRECHT VOGT.
